GARMENT HANGER

Robert Gustin, Boston, Mass.

Application October 21, 1937, Serial No. 170,170

5 Claims. (Cl. 211—119)

The present invention relates generally to hangers for garments, more particularly to hangers for garments of an elongated, plane character, and specifically to hangers for neckties, scarfs and similar articles of wearing apparel, whose lengths greatly exceed their widths.

It is a fact familiar to everyone, that garments such as neckties, scarfs and trousers, when draped over supports such as rods or bars, readily slip off of such supports unless the weights of such garments are distributed fairly evenly on both sides of the supports. For such garments, hangers comprising various means for clamping or engaging the garments, have been provided, but the use thereof invariably produces undesirable creases or other disfiguring marks upon the garments.

Therefore, the primary object of the present invention is to provide for garments of the character described a hanger from which, without the use of any clamping or engaging means, such garments are effectively restrained from slipping and falling.

Another object of the present invention is to provide for garments of the character described a hanger, utterly simple in construction, readily manipulable in use and economical to manufacture by the use of unelaborate mechanical means.

The present invention, in its broadest aspect, 30 contemplates the combination of a means for suspending a garment of the character described draped thereover, a means for supporting the means of suspension, and a means for displacing both thicknesses of the draped garment laterally 35 from the planes wherein they would otherwise hang, so that frictional contact between the two thicknesses of the garment will obviate all possibility of slipping of the garment from the hanger.

Other objects and advantages and desirable 40 features of the present invention will appear in the course of the following description of three illustrative embodiments of the spirit thereof.

In the accompanying drawing forming a part 45 of this specification, in which like numbers of reference, whenever they occur, denote like parts,

Fig. 1 is a front elevation of the first embodiment of the present invention, while

Fig. 2 is a side elevation thereof;

Fig. 3 is a front elevation of the second embodiment of the present invention, while

Fig. 4 is a side elevation thereof;

Fig. 5 is a front elevation of the third embodiment of the present invention, while

Fig. 6 is a side elevation thereof; and

Fig. 7 is a view, partly in section, along the line

1, 7 of Fig. 1, illustrative of the mode of functioning of these hangers.

In Figs. 1 and 2, the hanger shown is constructed of two pieces of stout wire: one piece, at one of its ends, is formed into the hook 1, is bent at successive points to form the sloping member 2, the upper side member 3 and the horizontal suspension member 4, and terminates in the coil 5; the second piece of wire, at one of its ends, is formed into the coil 6, encircling the first 10 piece of wire at the base of the hook 1, and is bent at successive points to form the sloping member 7 and the upper side member 8; after passing through the coil 5, the second piece of wire is bent outwardly from the plane of the hook 1 and the horizontal suspension member 4 to form the lower side member 9, is bent to form the horizontal displacing member 10, is bent inwardly toward the plane of the hook 1 and the horizontal suspension member 4 to form the lower side 20 member 11 and terminates in the coil 12 encircling the horizontal suspension member 4. In this manner is formed a hanger comprising a hook, a horizontal suspension member and a horizontal displacing member, the horizontal suspension member and the horizontal displacing member lying in a plane angularly disposed to the plane wherein the hook and the horizontal suspension member lie.

In Figs. 3 and 4, the hanger shown is constructed of a single piece of stout wire which, at one of its ends, is formed into the hook 13 and is bent at successive points to form the sloping member 14 and the upper side member 15; then, it is bent upon itself to form the horizontal suspension member 16, is bent outwardly from the plane of the hook 13 and the horizontal suspension member 16 to form the lower side member 18, is bent to form the horizontal displacing member 19, is bent inwardly toward the plane 40 of the hook 13 and the horizontal suspension member 16 to form the lower side member 20, is bent upon itself to form a second horizontal suspension member 21 in alignment with the first horizontal suspension member 16, is bent at successive points to form the upper side member 23 45 and the sloping member 24, and terminates in the coil 25 encircling the wire at the base of the hook 13. As is shown in Fig. 3, the ends of the horizontal suspension members 16 and 21 are in close proximity but do not meet, being separated by a small gap. To prevent, during the use of the hanger, any separation of those portions of the wire constituting the horizontal suspension members 16 and 21, one or more twists thereof may be intro- 50 55

duced, as at 17 and 22. In this manner is formed a hanger comprising a hook, a pair of horizontal suspension members in alignment and a horizontal displacing member, the horizontal suspension members and the horizontal displacing member lying in a plane angularly disposed to the plane wherein the hook and the horizontal suspension members lie.

In Figs. 5 and 6, the hanger shown is constructed of a single piece of stout wire which, at 10 one of its ends, is formed into the hook 26, and is bent at successive points to form the sloping member 27, the upper side member 28 and the horizontal suspension member 29; then, it is bent 15 upon itself to form the upper side member 30, is bent outwardly from the plane of the hook 26 and the horizontal suspension member 29 to form the lower side member 32, is bent to form the horizontal displacing member 33 and is finally 20 bent upwardly and outwardly to form the extension 34, substantially perpendicular to the plane of the lower side member 32 and the horizontal displacing member 33. To preserve, during the use of the hanger, the original conformation of 25 the upper side member 30, one or more twists thereof may be introduced, as at 31. In this manner is formed a hanger comprising a hook, a horizontal suspension member and a horizontal displacing member, the horizontal suspension member and the horizontal displacing member lying in a plane angularly disposed to the plane wherein the hook and the horizontal suspension member lie.

The modes of employing each of the three embodiments of the present invention differ slightly, but the function performed by each of the three hangers is identical. In using the first type of hanger, the garment is threaded into the hanger, as is shown by the curved arrow in Fig. 2. In 30 using the second type of hanger, the garment is folded upon itself, and one thickness thereof is inserted through the gap between the ends of the horizontal suspension members, and both thicknesses of the garment are then allowed to drape 35 from the horizontal suspension members and to rest upon the horizontal displacing member. In using the third type of hanger, the garment is draped upon the horizontal suspension member and is then shifted to the right hand side of the 40 hanger; the rear thickness of the garment is then passed inwardly over the extension of the horizontal displacing member, and both thicknesses of the garment are then allowed to rest against the horizontal displacing member. In the use of 45 all three types of the hanger, the garment is finally disposed, as is shown in Fig. 7, with the two thicknesses of the garment held in mutual contact against the horizontal displacing member by their weights, and, irrespective of the 50 shortness in length of the under thickness of the garment, such contact is sufficient to prevent the garment from slipping upon the horizontal suspension member to fall from the hanger.

The effectiveness in the functioning of the 55 present invention depends greatly upon the magnitude of the angle Y, shown in Fig. 6, between the plane wherein the hook and the horizontal suspension member lie and the plane wherein the horizontal suspension member and the horizontal 60 displacing member lie. In practice, I have found that values for this angle within the range 90° to 135° are satisfactory, while, with values less than 90°, the hanger tends to cause horizontal creases in the garments, and, with values appreciably greater than 135°, the hanger tends to

function poorly, i. e., the frictional contact between the two thicknesses of the garment is not always adequate to prevent the garment from slipping upon the horizontal suspension member to fall from the hanger. 5

The horizontal displacing member has been so termed because its purpose is to displace both thicknesses of a garment supported by the horizontal suspension member from the planes wherein they would otherwise lie to planes substantially parallel thereto, in order to create, by such displacement, a force perpendicular to the plane wherein the horizontal suspension member and the horizontal displacing member lie, to press together the two thicknesses of cloth in the region of the horizontal displacing member.

It is obvious that the second type of hanger is particularly suitable for use as a hanger for men's suits, provided that the wire used in its construction, and, more particularly, in the construction of its horizontal suspension members, possesses stiffness sufficiently great to support, without the deformation thereof, the weight of a pair of trousers.

While I have described and illustrated in detail 25 three embodiments of the present invention, these descriptions and drawing are merely illustrative, and not definite, of the invention, and various modifications thereof, within the scope of the appended claims, may be made without departing 30 from the character of the invention.

What I claim as my invention is:

1. A garment hanger comprising, in combination, a horizontal suspension member, a hook rigidly secured to the horizontal suspension member, and a horizontal displacing member rigidly secured to the horizontal suspension member and disposed parallel to, and at a sensible distance from, the horizontal suspension member, the horizontal suspension member and the horizontal displacing member lying in a plane disposed to the plane wherein lie the horizontal suspension member and the hook at an angle substantially equal to 135°. 35

2. A garment hanger comprising, in combination, two horizontal suspension members in alignment separated by an intervening gap, a hook rigidly secured to the horizontal suspension members, and a horizontal displacing member rigidly secured to the horizontal suspension members, and disposed parallel to, and at a sensible distance from, the horizontal suspension members, the horizontal suspension members and the horizontal displacing member lying in a plane disposed to the plane wherein lie the horizontal suspension members and the hook at an angle substantially equal to 135°. 45

3. A garment hanger formed out of a single length of wire bent to provide a supporting hook, a shaft for the supporting hook, and a frame comprising a horizontal displacing member and reentrant horizontal suspension members in alignment intermediate the horizontal displacing member and the supporting hook, the horizontal suspension members and the horizontal displacing member lying in a plane disposed to the plane wherein lie the horizontal suspension members and the shaft of the supporting hook at an angle substantially equal to 135°. 60

4. A garment hanger comprising, in combination, a horizontal suspension member, a hook provided with a shaft and rigidly secured to one end of the horizontal suspension member, and a horizontal displacing member rigidly secured to the other end of the horizontal suspen- 75

sion member and disposed parallel to, and at a sensible distance from, the horizontal suspension member, the horizontal suspension member and the horizontal displacing member lying in a plane disposed to the plane wherein lie the horizontal suspension member and the shaft of the hook at an angle substantially equal to 135°.

5. A garment hanger formed out of a single length of wire bent to provide a supporting hook, a shaft for the supporting hook, and a frame comprising a horizontal suspension member, a horizontal displacing member provided with an upwardly directed extension, a side member at

one end of the horizontal suspension member securing the horizontal suspension member to the shaft of the supporting hook, and a side member, provided with an upwardly directed prolongation, at the other end of the horizontal suspension member securing the horizontal suspension member to the horizontal displacing member, the horizontal suspension member and the horizontal displacing member lying in a plane disposed to the plane wherein lie the horizontal suspension member and the shaft of the supporting hook at an angle of substantially 135°.

10 ROBERT GUSTIN.
